UNITED STATES PATENT OFFICE.

ARTHUR TREVOR DAWSON AND GEORGE THOMAS BUCKHAM, OF LONDON,
ENGLAND, ASSIGNORS TO THE VICKERS, SONS & MAXIM, LIMITED, OF
SHEFFIELD, ENGLAND.

RUNNING-OUT SPRING FOR GUNS.

SPECIFICATION forming part of Letters Patent No. 640,541, dated January 2, 1900.

Application filed August 28, 1899. Serial No. 728,791. (No model.)

To all whom it may concern:

Be it known that we, ARTHUR TREVOR DAWSON and GEORGE THOMAS BUCKHAM, citizens of England, residing at 28 Victoria street, 5 Westminster, London, England, have invented a certain new and useful Improvement in Running-Out Springs for Guns, (for which we have applied for a patent in Great Britain, dated February 6, 1899, No. 2,662,) of which the following is a specification.

This invention relates to the construction of the running-out spring for a gun in such a manner that it can be readily adjusted to the required degree of compression, and when so 15 adjusted it can, when desired, be removed from the gun and cradle without having its adjustment altered.

For this purpose, as shown in longitudinal section in the accompanying drawing, the 20 spring *a*, which may be in several lengths, separated by washers *b*, is held in a tubular casing *c*, through which passes a central tubular bolt *d*. The rear end of this bolt, which is fixed by a retaining-nut *x* in a bracket *e*, 25 projecting down from the gun, has a shoulder, against which can bear a piston-shaped collar *f*, the boss of which can slide on the central bolt *d*, while its periphery fits within the tubular casing *c*. The front end of the 30 central bolt *d* is internally threaded to receive a compressor-screw *g*, the head of which bears on a piston-shaped collar *h*, like *f* at the rear end, so that by turning the screw *g*, and thus advancing this collar *h*, the spring is 35 compressed between it and the rear piston-shaped collar *f* to the desired extent. On the rear end of the tubular casing *c* is formed a sectional screw-thread or a set of sectional collars *k*, as on the breech-plug of a gun, and 40 on this is fitted a cap *l*, which has an internal flange bearing against the collar *h*. The tubular casing being attached, as at *m*, to the cradle in which the gun slides, the gun when

it recoils draws back the central bolt and the collar *h*, compressing the spring, which afterward, expanding causes these parts to move forward advancing the gun to firing position. 45

When it is desired to remove the spring, the retaining-nut *x* on the rear of the central bolt *d* is unscrewed. The casing *c*, spring *a*, 50 and the central bolt *d* can all be removed together without any alteration of the spring adjustment.

Having thus described the nature of this invention and the best means we know for 55 carrying the same into practical effect, we claim—

In a running-out spring for a gun, the combination of the tubular casing *c* attached to the cradle in which the gun slides, the spring *a* inclosed in said casing, the central tubular bolt *d* having its forward end internally screw-threaded, the bracket *e* depending from the gun, a nut *x* for securing the rear end of said bolt in said bracket, the rear piston-shaped collar *f* and the front piston-shaped collar *h* placed on said central tubular bolt in opposite ends of the tubular casing and between which collars the spring is held, the adjusting compressor-screw *g* inserted in the 65 internally-threaded forward end of the central tubular bolt with the head of said screw bearing against the forward collar *h*, and a cap *l* screwed onto the rear end of the tubular casing and provided with an internal 70 flange bearing against the rear collar *f*, substantially as and for the purposes described. 75

In testimony whereof we have hereunto set our hands in presence of two subscribing witnesses.

ARTHUR TREVOR DAWSON,
GEORGE THOMAS BUCKHAM.

Witnesses:

S. V. DAURIE,
HENRY KING.
